MULTITUBE HEATER FOR HOT GAS
RECIPROCATING ENGINES

Albert August Dros and Adriaan Koopmans, Eindhoven, Netherlands, assignors to Hartford National Bank and Trust Company, Hartford, Conn., as trustee

Application January 16, 1951, Serial No. 206,254
In the Netherlands February 10, 1950

5 Claims. (Cl. 60—24)

1

This invention relates generally to hot-gas reciprocating engines comprising a heater and more particularly to those engines whose heaters comprise a series of bent tubes.

According to the invention, such hot-gas reciprocating engines are characterized in that the tubes of the heater surround a space for the combustion gases which are caused to flow along the tubes. Each of the tubes is so arranged that one limb thereof opens into the hot cylinder of the engine and the other limb thereof opens into the regenerator space of the engine, the points of connection into the regenerator space jointly surrounding the points of connection into the hot cylinder. In addition, a group of similar limbs of the series of tubes are bent in such manner, that through a portion of their lengths, substantially equal passages for the combustion gases are formed between one limb emptying into the hot cylinder and two adjacent limbs emptying into the regenerator space.

It has been found that when a heater is provided with a series of bent tubes surrounding a space for the combustion gases, such as a combustion space, for example, and if of each tube one limb is arranged to empty into the hot cylinder and the other limb into the regenerator space of the engine, the group of limbs along which the combustion gases flow first will, as a rule, be heated to a higher degree than the others along which the gases later flow. In order to obviate this disadvantage, a group of similar limbs of the series of tubes are bent in such manner that through a portion of their length substantially equal passages for the combustion gases are formed between the limbs of both groups. Consequently, combustion gases of the same temperature flow along both groups of limbs, so that the temperature of the tubes will be lower than in the case where the combustion gases of the same temperature flow along the limbs of one group of tubes only.

In one embodiment of the invention, it is desirable for structural reasons that in each tube the distance between the bend and the extremity of the limb emptying into the regenerator space exceeds the distance between the said bend and the extremity of the limb emptying into the hot cylinder. This affords the advantage that a maximum amount of caloric energy is extracted from the combustion gases, thus considerably increasing the amount of heat transmitted to the series of tubes.

In one further embodiment of the invention,

5 the portions of the longer limbs projecting beyond the shorter limbs are provided with means for increasing the thermal transmission. Said means may be constituted by projections, such, for example, as fins.

10 In a further advantageous embodiment of the invention, the portions of the longer limbs projecting beyond the shorter limbs are provided with projections which are positioned transversely to said portions in such manner that the locally available combustion gases flow along said portions in a plurality of groups of parallel channels, which groups are provided in series. It is thus ensured that the combustion gases are brought into intimate contact with the tubes, with the result that the thermal transmission is even more improved.

15 The invention will now be described more fully by reference to the accompanying drawing, wherein:

20 Fig. 1 is a vertical cross-sectional view of a diagrammatic representation of a hot-gas reciprocating engine which is constructed in accordance with one embodiment of the present invention; and

25 Fig. 2 is a sectional view taken on the line II—II of Fig. 1.

30 In Fig. 1, a piston 2 and a displacer 3 reciprocate with a constant phase difference in a cylinder 4 by means of conventional crank mechanism (not shown). The piston 2 and the displacer 3 are connected by means of rods 14 and 15, respectively, to the aforesaid mechanism. The working medium contained in a hot space 4 flows through a group of tubes 5 enclosed in a casing 16, a regenerator 6 and a cooler 7 to a cold space 8. The inner group of limbs 5a of the group of tubes 5 are bent in such manner that through a portion of their length substantially equal passages for the combustion gases are formed between a limb of the group 5a and two limbs of the group 5b. The arrangement of the limbs is shown in the section II—II disclosed in Fig. 2. The heater is furthermore provided with a burner 9. The combustion gases flow from a centrally positioned combustion space 10 along the series of tubes, thus flowing simultaneously along the limbs 5a and 5b. Subsequently, the combustion gases confined within the said casing 16 pass along the portion 5c of the limbs 5b projecting beyond the shorter limbs 5a, thus giving off additional heat to the said tubes 5. In order to improve the thermal transmission, the said portions of tubes 5 are provided with groups of projections 11, posi-

tioned substantially at right angles to the limbs 5c and spaced from both the lower wall 16' of casing 16 and the outer wall 1' of cylinder 1. Baffle fins 17 are provided which extend alternately to said lower wall 16' and outer wall 1' so that the combustion gases flow along the said portions 5c of said tubes in a number of groups of parallel channels with each group extending in a different direction but in series with the others. The combustion gases finally leave the 10 heater via a conduit 12.

It is evident that the fins may be positioned in different ways. Thus, for example, it is possible that they may extend in the longitudinal direction of the tubes instead of transversely thereto.

In the embodiment above described, the tubes 5 are arranged concentrically about the combustion space 10 of the engine, the combustion gases being supplied centrally and leaving the heater at its periphery. It is obvious, however, that the construction according to the invention is also applicable when the combustion gases are supplied at the periphery of the group of tubes and carried away centrally. Furthermore, it is not required that, as is the case in Figs. 1 and 2, the limbs of the tubes are bent through a portion of their length in such manner that on a cross-section through this portion the cross-sections of the tubes are located on the same circle. The limbs may be bent through this portion in such manner that a zig-zag pattern is formed. To ensure satisfactory operation of the heater, it is necessary, however, that the passages for the combustion gases between the limbs be substantially equal.

Having described a preferred form of the present invention and certain modifications thereof, it will be evident that various changes therein may be made by persons skilled in the art without departing from the spirit and scope of the present invention. Consequently, it is to be understood that the foregoing description is to be considered illustrative of, rather than limitative upon, the appended claims.

What we claim is:

1. In a hot-gas engine having a hot cylinder and a regenerator, the improvement consisting of a heater for said engine, said heater comprising housing means enclosing a combustion space, burner means for said combustion space, a series of bent tubes located adjacent the inner surface of said housing means, each of said bent tubes comprising two limbs, one of said limbs being connected into the hot cylinder and the other limb being connected into said regenerator, the plurality of connections into said hot cylinder being in a group surrounded by the group formed of the plurality of connections into the regenerator, each of said bent tubes being so constructed and disposed with respect to one another that through a portion of the lengths thereof, substantially equal passages for the combustion gases are formed between a limb of one of said tubes connected into said hot cylinder and two of said other limbs of adjacent two tubes connected into said regenerator space.

2. In a hot-gas engine having a hot cylinder and a regenerator, the improvement consisting of a heater for said engine, said heater comprising housing means enclosing a combustion space, burner means for said combustion space, a series of bent tubes located adjacent the inner surface of said housing means, each of said bent tubes comprising two limbs, one of said limbs be-

ing connected into the hot cylinder and the other limb being connected into said regenerator, each of said one limb being shorter in length than is said other limb, the plurality of connections into said hot cylinder being in a group surrounded by the group formed of the plurality of connections into the regenerator, each of said bent tubes being so constructed and disposed with respect to one another that through a portion of the lengths thereof, substantially equal passages for the combustion gases are formed between a limb of one of said tubes connected into said hot cylinder and two of said other limbs of adjacent two tubes connected into said regenerator space.

3. In a hot-gas engine having a hot cylinder and a regenerator, the improvement consisting of a heater for said engine, said heater comprising housing means enclosing a combustion space, burner means for said combustion space, a series of bent tubes located adjacent the inner surface of said housing means, each of said bent tubes comprising two limbs, one of said limbs being connected into the hot cylinder and the other limb being connected into said regenerator, each of said one limb being shorter in length than each of said other limb, the plurality of connections into said hot cylinder being in a group surrounded by the group formed of the plurality of connections into the regenerator, each of said bent tubes being so constructed and disposed with respect to one another that through a portion of the lengths thereof, substantially equal passages for the combustion gases are formed between a limb of one of said tubes connected into said hot cylinder and two of said other limbs of adjacent two tubes connected into said regenerator space, and each of the portions of said longer limbs projecting beyond said shorter limbs provided with means to increase the thermal transmission thereto.

4. In a hot-gas engine having a hot cylinder and a regenerator, the improvement consisting of a heater for said engine, said heater comprising housing means enclosing a combustion space, burner means for said combustion space, a series of bent tubes located adjacent the inner surface of said housing means, each of said bent tubes comprising two limbs, one of said limbs being connected into the hot cylinder and the other limb being connected into said regenerator, each of said one limb being shorter in length than is said other limb, the plurality of connections into said hot cylinder being in a group surrounded by the group formed of the plurality of connections into the regenerator, each of said bent tubes being so constructed and disposed with respect to one another that through a portion of the lengths thereof, substantially equal passages for the combustion gases are formed between a limb of one of said tubes connected into said hot cylinder and two of said other limbs of adjacent two tubes connected into said regenerator space, and each of the portions of said longer limbs projecting beyond said shorter limbs being provided with fins for increasing the thermal transmission thereto.

5. In a hot-gas engine having a hot cylinder, and a regenerator, the improvement consisting of a heater for said engine, said heater comprising housing means enclosing a combustion space, burner means for said combustion space, a series of bent tubes located adjacent the inner surface of said housing means, each of said bent tubes comprising two limbs, one of said limbs being connected into the hot cylinder and the other

limb being connected into said regenerator, each of said one limb being shorter in length than is said other limb, the plurality of connections into said hot cylinder being in a group surrounded by the group formed of the plurality of connections into the regenerator, each of said bent tubes being so constructed and disposed with respect to one another that through a portion of the lengths thereof, substantially equal passages for the combustion gases are formed between a limb of one of said tubes connected into said hot cylinder and two of said other limbs of adjacent two tubes connected into said regenerator space, each of the portions of said longer limbs projecting beyond said shorter limb being provided with a plurality of transverse fins for increasing the thermal transmission thereto and baffle means associated with said limb portions for directing the

combustion gases from said combustion space to flow laterally past said finned limb portions in different directions past different groups of said fins along a continuous path.
